UNITED STATES PATENT OFFICE.

JAMES T. ATWOOD, OF ROCKFORD, ILLINOIS.

TOWROPE.

Application filed March 25, 1927. Serial No. 178,334.

This invention relates to towropes by which anything may be towed, and has for its principal object the provision of an improved towrope. My improvements are, 5 however, especially intended for use in towing motor vehicles.

It is well known that due to accidents, motor troubles and other similar mishaps, motorists are put to considerable inconvenience and delay because of the lack of a proper towrope. All sorts of improvised and make shift tows are devised by which the good Samaritan motorist attempts to tow his less fortunate motorist's car to the 10 nearest garage or out of the mud, as the case may be. A towrope such as contemplated by my invention may be carried by the average motorist along with his tool kit for these emergencies. To this end I have provided 15 a towrope so constructed as to be amply strong and durable for the purpose and adapted for quick connection to and disconnection from the most convenient parts of a car, such as the axle, spring shackle, 20 bumper, etc. The fastenings for the towrope are designed so as to prevent accidental disconnection and breakage while towing or getting underway. They are further constructed so as not to damage or mar the finish 25 of the parts of the car to which they are 30 adapted to be attached.

I have further aimed to provide as a new article of manufacture a towrope of the character described which will be simple and 35 easy to use and which may be produced economically and thus be within the purchasing range of the average motorist.

My invention will be better understood by 40 reference to the following description when considered in connection with the accompanying drawing, in which—

Figure 1 is a side elevation of a towrope embodying my invention;

Fig. 2 is an enlarged top view of the fastening at one end, showing it unfastened;

Fig. 3 is an enlarged section taken on the line 3—3 of Fig. 1;

Fig. 4 is a section through a modified form of hook and cable connection; and

Fig. 5 is an end view of the form shown in Fig. 4.

The rope or cable 5 may be of any material and construction suitable for the purpose. I have found, however, by experimentation, that by reason of the heavy 55 strains that a towrope is subjected to, spe-

cially by reason of the sharp and jerky pulls frequently encountered, a woven wire rope cable is best suited for this purpose. Each end of the cable is provided with a fastening means or device for connection to a convenient part of the car when pulling or towing. The cable, of suitable length, may be coiled when not in use, thus occupying but small 60 space for carrying.

As shown in Fig. 1 the fastenings at both ends of the cable (the length of which is not shown) are of the same construction. Each is characterized by an end portion adapted to be looped around a part of the car and fastened by means of a quick detachable connection to a hook on the cable. The construction of these fastenings being alike, a description of one will suffice. Two forms of hook and cable constructions are, 70 however, shown, and these will be described separately, referring first to that form shown in Figs. 1 to 3, inclusive.

As shown in Fig. 2 the end portion 6 of the cable is turned back upon itself to form a loop or eye 7 and the terminal end 8 is fixed to the cable proper by suitable means. In this form the wire stands of the end 8, as well as the cable proper at the point at which this end is to be fixed, are separated or spread and then intertwined so as to effect somewhat of a spliced connection. Soft metal is then poured in around the joint to make a permanent connection. With this form of connection I prefer to use a socket 90 part 9 which is strung onto the cable, over the joint just described. The soft metal 11 is poured into this socket part so as to fill 95 all the interstices, as shown in Fig. 3.

The socket part 9 is also utilized for securing a hook 12 to the cable, to which hook the loop end 7 is adapted to be attached as shown in Fig. 1. This hook, integral with the socket part 9 is so shaped as to securely hold the looped end of the cable and to prevent 100 accidental displacement thereof. To this end the throat of the hook is elongated and the end 13 is curved or turned inwardly to provide a stop for preventing the looped end of the cable from slipping off of the hook.

It will be noted that the end portion of the cable is doubled, so that when looped around a part and fastened to the hook 12 it is under tension tending to straighten out. This tendency or pressure of the looped end 110 7 outwardly against the hook 12 aids in preventing accidental displacement of the

looped end from the hook. The end 13 in the form of a reverse curve further prevents displacement in the event that the looped end 7 should shift. Thus the fastening is 5 effectually secured and there is little or no chance for it to become disconnected after having once been properly connected. It should also be observed that by making the hook integral with the socket part the end 10 connection is brought close to the cable and to the line of pull, thus avoiding abrupt angles and any tendency to pull out of line. Furthermore, by reason of this construction, an especially strong hook or mounting there- 15 for is provided, since the socket part is in effect a part of the hook and has a solid and substantial mounting on the cable. It will also be observed that the double cable at the end gives a wider and stronger means 20 for connection to the car or other object.

In the preferred embodiment of my invention a suitable sheath is provided for holding the double cable close together except at the end. Any suitable means may be pro- 25 vided for this purpose, although I prefer to employ a sheath which will also serve as a protection to both the cable and the part around which the cable is to be looped, thus preventing marring or scraping of the finish 30 of the latter. As shown, the sheath 14 is in the form of a length or section of rubber hose which by reason of its fabricated, multi-ply body serves very well for this pur- pose.

35 In Figures 4 and 5 I have shown another form of hook connection, comprising two parts 15 and 16, each having cable sockets 17 provided with wire scorings 20 in and between which the cable 5 and the end 8 are 40 adapted to be clamped by bolts 18, as shown. The part 15 has formed integral therewith a hook 19 similar in shape and for the same

purpose as the hook 12 above described. A lip 21 on each part 15 and 16 at the end from which the cable 5 emanates, prevents cutting 45 of the cable by wear against this edge. This form of connection does not require a core for casting. It will also be noted that the double cable will be given a quarter turn 50 between the hook connection and its loop end when being fastened to the hook 19.

I claim:

1. A towrope comprising a wire rope cable one end portion of which is turned back upon itself to form an eye, a fastening device for securing the terminal end of said turned back portion to the cable body, said fastening device having a hook over which said eye end of the cable is adapted to connect, the said hook having a reverse curve 60 whereby to prevent accidental withdrawal of the cable eye from connection with the hook. 55

2. A towrope comprising, a wire rope cable each end of which is turned back upon itself to provide a double cable loop end, op- 65 posed clamping parts for each end of the cable having matched grooves in contiguous parallel relation for the reception of the terminal end of the cable and the adjacent cable proper, fastening means passing 70 through both of the said clamping parts be- 75 yond the grooves for fixedly clamping said parts to the interposed cable portions, one of said clamping parts having a hook formed integral therewith in close proximity to the cable, and a sheath for each end of the cable enclosing and confining the double cable be- 80 tween the clamping parts and the loop end leaving the said loop end open for direct re- ception of the hook when passed around a part to be connected. 80

In witness of the foregoing I affix my signature.

JAMES T. ATWOOD.
